United States Patent Office

Des. 196,818
Patented Nov. 5, 1963

196,818

JAR

Bruce L. Roberts, Rossford, Ohio, assignor to Owens-Illinois Glass Company, Toledo, Ohio, a corporation of Ohio

Filed May 9, 1962, Ser. No. 70,054

Term of patent 14 years

(Cl. D58—25)

FIG. 1

FIG. 2

The back and side not shown are the same as the front and side shown.

I claim:

The ornamental design for a jar, substantially as shown and described.
